UNITED STATES PATENT OFFICE.

JOHN F. WHITE, OF CHICAGO, ILLINOIS, ASSIGNOR TO WHITE PRODUCTS COMPANY, OF CHICAGO, ILLINOIS, A CORPORATION OF ILLINOIS.

RADIATOR-CAP LOCK.

Application filed September 18, 1920. Serial No. 411,254.

To all whom it may concern:

Be it known that I, JOHN F. WHITE, a citizen of the United States, residing at Chicago, in the county of Cook and State of Illinois, have invented certain new and useful Improvements in a Radiator-Cap Lock, of which the following is a specification.

This invention relates to radiator cap locks, that is to say, to mechanism for securing an automobile radiator cap, on which a motor meter may be mounted, on the automobile radiator nipple in such a way as to prevent unauthorized removal thereof. It accomplishes this purpose without necessitating any modification of the radiator nipple and in a very simple and effective manner, by the construction illustrated in the accompanying drawing, in which—

Fig. 1 is a central vertical section through a radiator nipple and cap equipped with my invention;

Fig. 2 is a bottom view, the nipple being in section; and

Fig. 3 is a diametrical vertical section transversely of Fig. 1.

In these views, the numeral 1 designates the radiator nipple, 2 the body of the cap, 3 the arms thereof, and 4 the screw-threaded portion in the lower side of body 2, by which it is removably mounted on the nipple 1. Numeral 5 designates a circular opening in the top of body 2 for the reception of the stem of a motor meter or ornament (not shown), and 6 a counterbore or recess about the opening 5, for the reception of the means (not shown) by which the meter is secured to the cap.

A cylindrical lock-casing 7, of well known construction, is secured within the cap to one side of its center by a rivet connection 8, and is provided with the slidable bolts or tumblers 9, adapted to be projected and retracted by the usual key, shown in dotted lines at 10 in Fig. 1, insertable in the slots 11. Numeral 12 designates a cam dog pivotally mounted on a pin 13, secured in the cap body 2 to one side of its center at 90° from the lock casing 7, as clearly appears in Fig. 2. A spacer 14 is interposed between the dog 12 and the top of recess 4 to properly locate said dog in the plane of the bolts 9. The dog has a long operating arm 16 disposed for engagement by the lock tumblers 9 at one side of the cylinder and a short eccentric cam arm, or wedging nose 17

adapted to frictionally engage the inside surface 15 of the radiator nipple 1.

The device operates as follows:

After the cap has been screwed on the radiator nipple, the key is manipulated to project the bolts or tumblers 9 so that those arranged for cooperation with the dog engage its operating arm and swing it on its pivot, which places the dog in the full line position of Fig. 2, in which the nose 17 is pressed against the surface 15. Now any attempted rotation of the cap to the left to remove it from the radiator nipple will tend to rotate the dog on its pivot in such fashion as to swing the major axis of the cam arm 70 toward the surface 15, thereby wedging the nose 17 still more forcibly against the surface 15, and making it impossible to unscrew the cap. When it is desired to remove the cap, the key is inserted and operates to 75 retract the bolt or tumblers 9, whereupon the cam dog is free to swing into the dotted line position in Fig. 2, in which the nose 17 is free from the surface 15 and offers no resistance to the rotation of the cap.

Various modifications in the details and assemblage of the device may be made without departure from the spirit of the invention, as, for instance, the contour of the cam dog may be such as to require unlocking by 80 means of the key when the cap is to be placed on the radiator, although preferably the construction illustrated is employed wherein the cap can be turned freely, in a right hand or clockwise direction even when locked, the 85 cam only engaging the surface 15 effectively when it is attempted to be removed by rotation in a left hand or counter-clockwise direction.

Moreover, while I have illustrated and 90 described the invention as applied to the locking of a radiator cap in position, it will be evident that the same is applicable in 95 may relations to the locking of a cap upon a nipple or stud to prevent unauthorized tampering therewith.

Other changes will readily occur to the skilled mechanic as within the scope of the invention as defined in the appended claims.

I claim:

1. A lock for radiator caps and the like, comprising a locking dog pivotally mounted within the cap and having a nose adapted to engage and bind against the inner surface of the radiator nipple, and a key-operated 110

bolt within said cap movable into and out of cooperation with said dog to control its position.

2. A lock for radiator caps and the like, comprising a locking dog pivotally mounted within the cap and having a nose adapted to engage and bind against the inner surface of the radiator nipple, and a lock casing mounted in said cap and operable from outside by a key and comprising a slidable bolt movable into and out of cooperation with said dog and effective to press the same into operative relation to the nipple.

3. A lock for radiator caps and the like, comprising a cam dog pivoted within the cap and consisting of an operating arm and nose adapted to engage the radiator nipple, and a lock casing protectively mounted within the cap and having a sliding bolt movable into engagement with said arm to press said nose against said nipple.

4. A lock for radiator caps and the like, comprising the combination with the cap of a key-operated lock casing mounted within the cap and having a horizontally slidable bolt and a locking dog pivoted within the

cap and having an operating arm lying in the path of the bolt and a cam nose adapted to cramp against the inner surface of the radiator nipple, whereby when said bolt is projected said nose will be forced into locking engagement with said surface and the turning of the cap in a direction to remove the same will be prevented.

5. A closure, comprising the combination with a tubular mounting, of a cap having screw engagement therewith to close the same, said cap having laterally-extended handles whereby it may be rotated on said mounting, a dog carried by the cap and adapted to bind against the mounting under pressure from said handles to prevent rotation of the cap, and a key-operated bolt movable into engagement with the dog to effect its operative engagement with the mounting.

In testimony whereof I have hereunto signed my name in the presence of two subscribing witnesses.

JOHN F. WHITE.
